CLAIR L. FARRAND, OF FOREST HILLS, NEW YORK, ASSIGNOR TO LEKTOPHONE CORPORATION, OF NEW YORK, N. Y., A CORPORATION OF DELAWARE

SOUND CONTROL APPARATUS

Original application filed April 23, 1921, Serial No. 464,009. Divided and this application filed October 17, 1925. Serial No. 63,042.

My invention relates to apparatus for the intercontrol or interconversion of electrical energy and sound for any suitable or desired purposes, as for example, telephony, photography, amplification of sound or of sound-representing electrical energy, or other kindred or analogous purposes.

The present application is a division of my co-pending application Serial No. 464,009 filed April 23, 1921.

In accordance with my invention I employ for sound reproduction or control by sound, in association with a diaphragm or tympanum relatively large in diameter as compared with usual or common telephone or phonograph diaphragms, and comprising a substantially rigid vibrating conical or equivalent section, yieldingly supported by a circumferentially extending ring or flange section, electro-magnetic means utilizable either for vibrating the diaphragm to produce sound, or actuated or controlled by the diaphragm for producing or controlling sound-representing electrical energy, said electro-magnetic means comprising a field magnet having opposed polar faces forming an air gap between them, and an armature having a direct coaxial connection with the diaphragm and which is reciprocable in the air gap in a path parallel with the polar faces.

Further in accordance with my invention, the diaphragm and the electro-magnetic means are so positioned or disposed relatively to each other as to form a compact structure suitable for various purposes, as for example, portable sound reproducer or telephone transmitter or loud talking receiver.

The invention is illustrated in the accompanying drawing which is a vertical longitudinal section, partly in elevation, of sound-producing apparatus embodying my invention.

Referring to the drawing, D is a diaphragm or tympanum of suitable material and structure, such, for example, as disclosed in Hopkins Patent No. 1,271,529, July 2, 1918. The diaphragm D proper is conical, as indicated, or of other or equivalent formation, and has its integral circumferential ring or flange α rigidly clamped or held between the

clamping rings b and c secured to each other by any suitable means, as by screws d . The diaphragm D has a portion α' which forms with the walls of the cone an abrupt bend and thereby constitutes a flexible rim for 55 flexibly connecting the conical portion of the diaphragm to the support. The ring c is provided, if desired, with a pin n which is received in an aperture in the portable or other base member o . Attached to the ring c are 60 the inwardly extending arms e .

Integral with or supported by the arms e is the cup-shaped magnetic field yoke member p disposed well within the concave or hollow side of the diaphragm D. The yoke member p , and also the arms e when integral therewith, may be of cast iron or other suitable magnetizable material. The central core member q , preferably of Norway or other soft iron, either in solid form or in laminæ 70 or wires, is supported at its right end in the back yoke member r forming the closure of the cup member p . At the other end of the cup member p is the circular pole member s , of cast iron or other suitable magnetizable 75 material extending radially inwardly and approaching the end of the core q , but spaced therefrom to leave an air gap or space within which may vibrate, longitudinally of the axis of the conical diaphragm D, a coil or winding M wound circumferentially upon and secured 80 to the cylindrical form or frame t of insulating material having at one end the arms or spider u secured to the pin or rod v , which is secured to the diaphragm D at its center 85 and apex by the clamping nut w . Disposed within the yoke member p and surrounding the core q is the magnetizing winding W for producing an intense magnetic field in the gap between the pole member s and the core q in which is disposed the aforesaid winding M. The winding W is traversed by current 90 of suitable magnitude from any suitable source. The terminals of the winding W are 95 connected to the binding posts x , x , and the terminals of the coil M are connected by flexible conductors y , y , extending through a bore in the core q to the binding posts z , z , which, and the binding posts x , x , are carried upon 100

M. The winding W is traversed by current of suitable magnitude from any suitable source. The terminals of the winding W are 95 connected to the binding posts x , x , and the terminals of the coil M are connected by flexible conductors y , y , extending through a bore in the core q to the binding posts z , z , which, and the binding posts x , x , are carried upon 100

the block *a*1, of insulating material, secured to the member *r*.

When the winding *W* is traversed by current so producing an intense magnetic field for the coil *M*, and when the coil *M* is traversed by fluctuating or varying electric current, the coil *M* will be with correspondingly variable degree attracted and moved axially of the conical diaphragm *D* and transmit thereto corresponding vibrations, which vibrations are substantially distortionless as regards their representation of the wave form of the electric current through the coil *M*, and such vibrations of the diaphragm *D* are without substantial distortion converted into sound waves in the surrounding air, which sound waves represent without substantial distortion the variations in the current traversing the coil *M*. In this aspect the structure described is a telephone receiver for producing amplified sound waves which may readily be heard at substantial distances from the diaphragm *D*.

Conversely, with the winding *W* energized, upon production of speech or sound waves in the vicinity of the diaphragm *D* it will vibrate in substantially distortionless accord with those sound waves and transmit the vibrations to the coil *M*, whose corresponding movements in the intense magnetic field will cause generation in the coil *M* of electric currents whose wave forms are in substantially distortionless accord with the uttered speech or sound waves. In this aspect the apparatus is a telephone transmitter and has decided advantages over the ordinary carbon or other microphone used in telephony in that the wave form of the sound-representing current corresponds substantially exactly with the uttered speech or sound waves.

For purposes both of reception and transmission it is desirable that the total mass or inertia of the coil *M*, support *u* and pin *v* shall be as small as possible in order that the diaphragm *D* shall be loaded or damped as little as possible, and thereby avoid modification or disturbance of its own characteristics.

It is further advantageously characteristic of the structure above described that the forces exerted by the coil *M* upon the diaphragm *D*, or vice versa, are, as to their direction, co-axial with the cone *D*, and originate close thereto and are not transmitted through long or massive intervening members.

It will be understood that the structure described may be utilized for other or various purposes, as for example, for converting into sound audible throughout a room radio telegraphic or telephonic signals, as when connecting the coil *M* in place of or in association with the telephone receiver commonly employed in radio receiving apparatus.

In general, when there is to be control or

conversion into sound by or from electric energy, or vice versa, and which I term intercontrol or interconversion, it is desired, that the mass or inertia of the movable structure of the electrical apparatus and its mechanical connection to the diaphragm *D* shall be as small as possible consistent with desired magnitude of the vibratory forces involved.

A loudspeaker constructed as herein disclosed, that is, one having a direct-acting diaphragm comprising a substantially rigid central portion connected to a support by a flexible rim and actuated by an armature coaxially connected with the rigid portion of the diaphragm and moving in a path parallel with the polar faces has the following important advantages; the total elastic restoring force, localized in the diaphragm and its flexible rim, may be kept down to that small and predetermined value that will cause the diaphragm to produce the sound waves directly in the surrounding air without sensible resonant distortion. In other words, the fundamental period of the tympanum will lie far down in the working range of frequencies. The armature by reason of its freedom from elastic restoring force of its own, adds nothing to the elastic restoring force of the diaphragm and does not upset or disturb the advantageous characteristics of the diaphragm.

Radio broadcasting and receiving apparatus, including amplifiers, has been developed to the point where it is possible to obtain amplified currents, representing the original sounds, practically free from distortion. The elements of the above described combination coact to produce a distortionless apparatus capable of receiving these undistorted currents and reproducing them in a distortionless manner.

I claim:

1. The combination with a conical tympanum of a coil substantially coaxial therewith and disposed within the same on the concave side thereof, a field magnet for said coil disposed on the concave side of said tympanum within the same, and an axial connection between said coil and the apex of said tympanum.

2. The combination with a conical tympanum, of a support to which the periphery of said tympanum is secured, a field magnet support extending from said support toward the axis of said tympanum on the concave side thereof, a field magnet carried by said last named support, a coil coaxial with said tympanum disposed in the field of said magnet, and a connection from said coil to the apex of said tympanum.

In testimony whereof I affix my signature.
CLAIR L. FARRAND.
